UNITED STATES PATENT OFFICE.

GEORG LEUE, OF BERLIN, GERMANY.

CHUTE FOR ENDLESS-ROPE TRANSPORTING APPLIANCES.

Patented Oct. 8, 1907.

Specification of Letters Patent.

Application filed August 18, 1905. Serial No. 274,743.

No. 867,584.

To all whom it may concern:

Be it known that I, GEORG LEUE, a citizen of the German Empire, and a resident of Berlin, (whose post-office address is Kurfürstendamm 24,) have invented certain new and useful Improvements in Chutes for Endless-Rope Transporting Appliances, of which the following is a specification.

My invention relates to a chute for receiving the load delivered at a certain point of an endless-rope transporting appliance. The device is more particularly adapted for use with appliances for transhipping cargoes at sea, when, owing to motion of the vessel, the place at which the goods drop from the rope is continually changing in position, thus rendering expedient unloading of the same a matter of much difficulty. In such appliances the rope is usually passed over a pulley, mounted with capability of oscillation on the mast of the ship; and the sacks containing the coal or other goods being transhipped are hung on the rope, but on means of hooks, which normally grip the rope, but on arrival at the place where the goods are to be shot, are released automatically, so that the sack together with the hook falls off. A free fall of the sacks on the deck naturally injures their contents, wherefore attempts have been made to provide the device which carries the rope-pulley with a rail, which partakes of all the oscillations of the pulley and on release of the hook is seized by a gripping-device attached to the latter. The sack can then travel down the rail and a wire rope connected thereto so as to form an extension of the said rail, and is thus conducted to the deck. It frequently occurs, however, that the gripper does not seize the rail; and another defect is that the instability of the wire rope is relatively great, so that the direction of the rigid rail is liable to prolongation.

It is an object of my invention to provide a device for preventing the prolongation of the wire rope, so as to deliver the sacks to the deck in a safe and rapid manner.

so that the rope is independent of lateral oscillations of the vessel. The sack *f* is hung on the rope by means of the hook *g*, in which manner it can be conveyed toward the mast. In the path of the hook is a stop *h*, secured to the frame *i*, mounted loosely on the pulley *j*, which rests on the rope, so that the frame *i* shares the movements of the latter. On the hook striking the stop *h* its grip on the rope is released automatically and the sack with the hook falls down. This apparatus is in itself well known. The essential feature of my invention is the provision in such appliances of a flexible tubular chute *m* of textile fabric or other material, which receives the sack and delivers it upon the deck. The upper mouth of the chute *m* is provided with a rigid frame *n* of iron or other material, which may be of bifurcated, annular, or other suitable form. This frame is secured in horizontal position directly below the place where the sack is released from the rope. It may be attached direct to the mast *e* itself, but it will be found advantageous to secure it to the bracket *c* in the rope pulley *b* is mounted, so that it may follow the lateral oscillations of the rope.

The advantage of this method over prior art is that a free descent of the flexible sack is absolutely guaranteed, while in view of the flexible character of the lower mouth or outlet can be located at any desired place on the deck, or of the vessel, there being no rigid members.

Having thus described my invention as new and desire to secure by Letters Patent an endless-rope transporting appliance and a horizontally swinging pulley and a load-carrying hook secured automatically and rigidly to the deck, so as to share the lateral oscillations of the place, rigid means secured thereto being flexible, so as to open by the said means the inlet open by the said means, while the goods are delivered.
